UNITED STATES PATENT OFFICE.

FRIEDERICH MÜLLER, OF HARTFORD, CONNECTICUT, ASSIGNOR TO PRATT & WHITNEY COMPANY, OF NEW YORK, N. Y., A CORPORATION OF NEW JERSEY.

CUTTER-GRINDING MACHINE.

1,338,319.

Specification of Letters Patent. Patented Apr. 27, 1920.

Application filed March 30, 1918. Serial No. 225,621.

To all whom it may concern:

Be it known that I, FRIEDERICH MÜLLER, a citizen of the United States, residing at Hartford, in the county of Hartford and State of Connecticut, have invented certain new and useful Improvements in Cutter-Grinding Machines, of which the following is a specification.

The invention relates to a grinding machine which is adapted to grind articles or blanks to predetermined sizes and shapes. In the preferred embodiment of the invention, as illustrated, the machine is adapted to grind milling cutters and to grind each tooth thereof so that its outer edge will conform to a predetermined contour. For this purpose use is made of an abutment and a former coöperating with the abutment to determine the contour. While the invention is not limited in all of its phases to a contour cutter grinding machine, or even to a plain cutter grinding machine, I will nevertheless, for the sake of convenience, use the word "cutter" in referring to the articles being ground. It will be understood, however, that this term, taken by itself, is not to be construed as limiting the scope of the invention.

One of the objects of the invention is to provide a machine of this class in which a definite relationship is maintained between the abutment and the line at which the wheel engages the cutter notwithstanding changes in diameter of the wheel and notwithstanding relative vertical adjustment. Preferably also a similar definite relationship is maintained between the former and the cutter tooth to be ground. A further object of the invention is to provide a wheel dressing mechanism having a peculiar coöperative relationship with the other parts of the machine whereby the wheel may be dressed at the aforesaid line. In the preferred embodiment of the invention, as illustrated, there is a fixed plane in which are located the edge face of the abutment, the wheel dressing tool and the line at which the wheel is dressed and at which it engages the cutter.

Another object of the invention is to provide a wheel dressing tool and a cutter support which are maintained in definite relationship to each other while relative adjust-

ment is effected between them and the grinding wheel.

Another object of the invention is to provide means whereby certain relative adjustments may be made between the cutter support and the former and between the wheel and the dressing tool.

Still another object of the invention is to provide improved means for supporting and adjusting the dressing tool and the cutter support and the former in adjustable relationship to each other.

An additional object of the invention is to provide improved means for maintaining a uniform pressure between the former and the abutment while relative movement is being effected between the cutter and the wheel.

A further object of the invention is to provide improved means for carrying the cutter support in such a way as to permit it to move relatively to the grinding wheel.

Still another object of the invention is to provide means whereby a plurality of formers are supported in such a way that any one of them can be used at will.

Additional objects of the invention will be apparent from the following specification and claims.

In the accompanying drawings I have shown the embodiment of the invention which I now deem preferable, but it will be understood that the drawings are intended merely for the purpose of illustration and are not to be construed as defining or limiting the scope of the invention, the accompanying claims being relied upon for that purpose.

Of the drawings:

Figure 1 is a front elevation of a grinding machine embodying the invention, certain parts being broken away.

Fig. 2 is an end view taken from the left, certain parts being broken away and others shown in section.

Fig. 3 is a view on an enlarged scale, partly in elevation and partly in section along the line 3—3 of Fig. 1.

Fig. 4 is a front view of the mechanism shown in Fig. 3, certain parts being broken away to expose other parts.

Fig. 5 is a plan view of the mechanism

shown in Fig. 3, the cover being removed and certain parts being broken away to expose other parts.

Fig. 6 is a fragmentary plan view, partly in section, showing the means for supporting the cutter to be ground.

The machine comprises a cutter support, preferably a former and an abutment therefor, a rotatable grinding wheel adapted to be located in a predetermined position preferably fixed in relation to the abutment, and means supplemental to the cutter for determining the said predetermined position of the wheel. This means is preferably a dressing tool for the wheel positioned in predetermined relation to the abutment. The cutter support holds the cutter so that the teeth thereof may be engaged successively by the wheel. The grinding face of the wheel intersects the plane of the front face of each tooth along a predetermined line, this line being preferably fixed and the wheel being adjustable to maintain the said line in fixed position as the wheel diameter changes. A fixed relation is maintained between the abutment and the aforesaid line, the abutment being preferably in perpendicular alignment with the line. Inasmuch as the abutment is in fixed relation with the said line, this same relation must be established between the former and the cutter. The former and the cutter support are therefore relatively adjustable in order that this fixed relation may be brought about for cutters of different diameters. When a dressing tool is used, as is preferred, this tool is formed as a permanent part of the machine and is mounted to engage the grinding face of the wheel along the said predetermined or fixed line. The tool is thus ground along the same line at which it is effective for grinding. The before mentioned adjustment of the wheel makes it possible for the wheel to be moved into engagement with the dressing tool, the tool itself being normally movable only along the aforesaid line.

I herein use the terms "vertical" and "horizontal" in describing the several movements and adjustments of the parts. It will be understood that these terms are used merely for the purpose of expressing the relations of the several movements and adjustments and are not to be construed literally as limiting the scope of the invention.

The rotatable grinding wheel is shown at 1. The cutter support includes an arbor 2 for holding the cutter A to be ground. The axes of the wheel and of the arbor extend in the same general direction and are preferably at or near the same level, although relative vertical adjustment is possible, as will presently appear. Devices are provided for supporting and relatively adjusting the wheel 1 and the arbor 2 in the manner al-

ready outlined so as to permit the cutter A to be engaged with the wheel and ground to the proper contour.

There is provided a main frame 3 upon which all of the other parts of the machine are supported. The wheel is carried by a rotatable spindle 4 mounted in suitable bearings in the bracket 5. The spindle 4 carries a belt pulley 4^a around which a belt may pass to drive the spindle. In order that the wheel may be horizontally adjusted in parallelism forward or backward, the bracket 5 is secured to or formed as a part of a transverse slide 6 mounted on a guideway 7 on the top of the frame 3. The slide 6 may be moved by means of a screw 8.

In order that relative vertical adjustment may be effected between the cutter support and the wheel, I preferably provide means whereby the cutter support may be moved vertically, the wheel being fixed against vertical movement. As illustrated, the cutter support and associated parts are carried by a slide 9 which is adjustable along a vertical guideway 10. Vertical movement may be effected by means of a screw 11, this screw being connected through bevel gearing 12 with a horizontal shaft 13. This shaft 13 has a squared end by means of which rotative movement can be imparted to rotate the screw 11 and thus raise or lower the slide 9 and the parts carried thereby, including the cutter support. Preferably a horizontal longitudinal cross rail 14 is secured to the slide 9. A saddle 15 is longitudinally movable along the cross rail, this saddle carrying the cutter support by means of intermediate devices to be described.

The cutter support is horizontally movable with respect to the saddle, preferably angularly. Mounted on the saddle 15 for swinging movement about a vertical axis is a turntable 16. Preferably the turntable 16 is also adjustable forward and backward with respect to the saddle. As illustrated, the saddle is provided with a transverse guideway in which is fitted a slide 17. This slide 17 has a depending boss 18 provided with a vertical aperture in which is fitted a pivot stud 19 carried by the turntable 16. At the lower end of the boss 18 is a screw 20 having a conical end which engages the bottom of the stud 19 and serves as a bearing.

The turntable 16 is provided near its top with a transverse guideway in which is fitted a slide 21 adjustable by means of a screw 22. The slide can be locked in adjusted position by means of a screw controlled by a handle 23. Carried by the slide 21 are the cutter arbor 2 and the other devices constituting the cutter support, as shown in Fig. 6. The cutter A is adapted to be mounted on the arbor 2, being spaced at the proper distance by means of a washer 24. A nut 25 serves to hold the

cutter in place. The cutter must be so positioned that the tooth to be ground is positioned with its front face at an angle to the grinding face of the wheel, the tooth face 5 being horizontal in the present case as shown in Fig. 3. The teeth must be successively moved to this position as the grinding operation proceeds, and I provide a stop mechanism for holding the cutter teeth successively in the grinding position. Preferably there is a finger 26 which is carried by a rocker 27 horizontally pivoted to a bracket 28 carried by the slide 21. A spring 29 tends to move the rocker 27 in the direction 10 to hold the finger 26 in engagement with one of the cutter teeth. A resilient finger 30 is provided for engaging the back of one of the cutter teeth to prevent backward movement of the cutter. With a cutter having 15 twelve teeth, as shown, the cutter is adjusted to bring the face of the uppermost tooth into engagement with the finger 26, the finger 30 engaging the back of one of the other teeth. In this position the horizontal tooth 20 adjacent the wheel is ground in the way to be presently described. Then the cutter is turned in the counter-clockwise direction so as to bring the next tooth into grinding position. The bracket 28 is vertically ad- 25 justable to accommodate cutters of different diameters. The bracket is provided with a vertical slot through which extends a bolt 31. By loosening this bolt the bracket may be moved vertically and then by tightening 30 the bolt the bracket will be locked in ad- justed position. It will be seen that the end of the finger 26 is moved vertically when the bracket 28 is moved, thus avoiding any ne- cessity for the adjustment of the finger so 35 long as cutters of the same number of teeth are to be ground.

As already stated, I provide a former to guide the grinding operation. The former is located vertically beneath the tooth which 40 is to be ground, and it engages an abutment which has a front or edge face in perpendicular alinement with the line of intersection between the surface of the wheel and the plane of the front face of the tooth to 45 be ground. In other words, the position of the abutment is such that a line perpendicular to the plane of the tooth face and passing through the line of intersection with the wheel will also pass through the edge 50 of the abutment. This abutment is indicated at 32, being carried by a stud 33 projecting upward from the saddle 15.

In order that the machine may be used 55 for grinding cutters of various sizes and contours with the minimum inconvenience and loss of time, I provide a plurality of formers any one of which can be readily moved into operative position to engage the abutment 32. As illustrated, the turntable 16 carries a longitudinal rotatable spindle 60 65 16 which can be manually turned by means of a knurled wheel 35. Carried by the spindle 34 is an index wheel 36 having a series of radial apertures or notches any one of which may be engaged by a spring- 70 pressed plunger 37. Secured to the index wheel 36 are formers 38 corresponding in number and spacing to the apertures of the wheel. These formers have contours which correspond respectively with the contours of 75 the various cutters which are to be ground on the machine. By withdrawing the plunger 37, the operator, by means of the hand wheel 35, can turn any desired former into position to engage the abutment 32. 80 This former will be locked in operative position by permitting the plunger 37 to engage the corresponding aperture in the wheel 36.

Before grinding can take place, the cutter 85 support must be vertically adjusted with respect to the wheel axis so as to bring the front face of the tooth to be ground at an elevation somewhat above the axis of the wheel. This is necessary in order that the 90 wheel may properly relieve the tooth. The exact difference in elevation will depend to some extent on the diameter of the cutter, on the diameter of the wheel and on the amount of relief required. 95

In operation, the cutter A is put in place on the arbor 2, as shown, and the corresponding former is indexed into operative position. Then, with the edge face of the former in engagement with the edge face of 100 the abutment 32, the slide 21 is adjusted forward by means of the screw 22 to bring the cutter into engagement with the grinding wheel 1 at the aforesaid line of intersection. Such engagement having been secured, the 105 slide 21 is locked in position and then the turntable 16 is swung about the axis of the pivot pin 19, the former 38 being kept at all times in firm engagement with the face of the abutment 32. For convenience of the 110 operator in moving the turntable 16, there is preferably provided a knurled handle 39. As already stated, the face of the abutment 32 is in perpendicular alinement with the line of intersection between the grinding 115 wheel and the plane of the cutter tooth, and it will therefore be clear that the cutter tooth will be ground so that every point along its contour is in perpendicular alinement with the corresponding point on the 120 former 38. When one tooth has been ground, the cutter is indexed and the next tooth is similarly ground, this operation being repeated until all of the teeth of the 125 cutter have been ground.

I have already stated that the pivotal axis of the turntable 16 is transversely movable, the pivot pin 19 being supported by the transversely movable slide 17. It is this transverse movement of the axis of the pivot 130

which makes it possible for the former to be held in engagement with the abutment notwithstanding the non-circular contour thereof. Preferably, however, in order that the movement of the slide 17 may be reduced to a minimum, the several formers 38 are so positioned on the wheel 36 that the approximate center of curvature of each of them is in alinement with the axis of the pivot pin 19 when the former is in operative position. Therefore, as shown in Fig. 3, the formers for the larger sized cutters project farther out from the wheel 36 than do the formers for the smaller sized cutters.

Preferably I provide means such as a spring whereby the former 38 is automatically held in engagement with the abutment 32 during the turning movement of the turntable. Such a means has important advantages in that it applies a pressure which is the same for all of the teeth of the cutter. If reliance were placed upon manually applied pressure, it would frequently happen that the operator would supply more pressure for one tooth than for another, thus springing the several parts to different extents and causing some teeth to be ground to a greater depth than others. The mechanism which is illustrated comprises a segmental gear 40 which meshes with rack teeth 41 formed on the under side of the slide 17. This segmental gear is mounted on a rock shaft 42 to which is secured a handle 43 and a depending arm 44 having a notch 45. Horizontally pivoted to the saddle 15 at 46 is a lever 47 carrying a spring-pressed plunger 48 adapted to be seated in the notch 45 in the arm 44. When the parts are in the positions shown in Fig. 3, the spring-pressed plunger 48 tends to swing the arm 44 and the gear segment 40 in the counter-clockwise direction, thus tending to move the slide 17 backward and to press the former 38 against the abutment 32. When one tooth has been ground, the operator, by means of the handle 43, can move the slide 17 back far enough to permit indexing of the cutter. It will be seen that this backward movement takes place against the resistance of the spring-pressed plunger 48. When the cutter has been completely ground, the lever 47 is moved to the position shown in Fig. 2, thus disengaging the plunger 48 from the lever 44. Then the operator, by means of the handle 43, can move the slide 17 back far enough to permit the cutter to be removed and a new one put in place. After that the slide 17 is restored to its original position and the lever 47 is moved back to the position shown in Fig. 3, the beveled lower end of the arm 44 forcing the plunger 48 backward and guiding it into the notch 45.

In order to protect the working parts as far as possible from dust and the products of abrasion, and also from water in case the

machine is used for wet grinding, I provide a cover 49 which fits over the turntable 16 and which coöperates with a skirt 50 formed on the turntable to entirely inclose the upper parts of the mechanism.

I have already stated that the line of intersection between the plane of the front face of the tooth being ground and the surface of the wheel is in perpendicular alinement with the edge face of the abutment 32; and I have stated that a dressing tool is provided whereby the wheel may be dressed from time to time as it wears. The dressing tool is so related to the wheel that the aforesaid line of intersection remains in the same relation to the abutment notwithstanding the successive dressings of the wheel. I provide a wheel dressing tool 51 which has its point located preferably in the vertical plane of the edge face of the abutment and preferably also in the plane of the front face of the tooth being ground, this latter plane in the present case being a horizontal one passing through the axis of the cutter arbor 2. Inasmuch as the dressing tool is to have its point always at the same level as that of the axis of the cutter arbor 2, the dressing tool is preferably so mounted that it will be vertically adjusted with the cutter arbor. As shown, the cross rail 14 carries a saddle 52 which preferably engages the same ways engaged by the aforesaid saddle 15. Secured to the upper part of the saddle 52 is a bracket 53 which extends endwise and which supports the dressing tool 51 at a position adjacent the wheel 1. Preferably the bracket 53 is removable so that the dressing tool will not be in the way of the operator during the grinding operation. As illustrated, the bracket 53 is slotted and is engaged by a screw 54 having a knurled head. The screw serves to hold the bracket 53 firmly in place during the wheel dressing operation, but by loosening the screw it is possible to remove the bracket. Secured to or formed on the bracket 53 is a boss 55 which has a vertical front surface accurately ground to lie in the same vertical plane as the front face of the abutment 32, this relationship being clearly shown in Fig. 2. This boss 55 serves as a guide for setting the dressing tool 51. In setting, the operator applies a straight edge to the boss 55 and then adjusts the tool so that its point contacts with the straight edge. The boss 55 in this way serves as a convenient means for locating the point of the dressing tool exactly in the vertical plane of the front face of the abutment 32. The position of the dressing tool 51 in the bracket 53 is such that the point of the tool lies in the same horizontal plane as the axis of the cutter arbor 2. When the dressing tool has been once adjusted it does not thereafter have to be moved except when necessary to

compensate for wear on the tool itself. No changes in the position of the tool are necessary on account of different sizes of cutters or different sizes of wheels.

- 5 When the dressing tool has been set as described, the wheel is adjusted forward into engagement with the tool by turning the screw 8. When the wheel has been brought into engagement with the tool the saddle 10 52 is reciprocated along the cross rail, thus carrying the tool across the face of the wheel. Preferably, for moving the saddle 52, there is provided a pinion 56 carried by a short transverse rotatable shaft 57 on the 15 saddle. The pinion 56 meshes with a rack 58 on the cross rail, and the shaft 57 is provided with a handle 59 by means of which it may be turned. The operator, by turning the handle 59, can move the saddle back and forth and thus move the dressing tool 20 back and forth across the face of the wheel.

What I claim is:

1. In a cutter grinding machine, the combination of a rotatable grinding wheel having a convex grinding face, a cutter support for holding a cutter in engagement with the face of the wheel and for moving it relatively to the wheel to effect grinding along a line which is predetermined and normally fixed notwithstanding differences in the size of the cutter, a dressing tool movable along the said fixed line, and means for adjusting the wheel into engagement with the tool whereby its grinding face is always maintained at the said line notwithstanding wear.

2. In a cutter grinding machine, the combination of a rotatable grinding wheel having a convex grinding face, a cutter support for holding a cutter in engagement with the face of the wheel and for moving it relatively to the wheel to effect grinding along a line parallel to the wheel axis, the said line being predetermined and normally fixed notwithstanding differences in the size of the cutter, a dressing tool movable along the said fixed line, and means for adjusting the wheel into engagement with the tool whereby its grinding face is always maintained at the said line notwithstanding wear.

3. In a contour cutter grinding machine, the combination of a rotatable grinding wheel, a cutter support for holding a cutter with the front face of a tooth substantially horizontal and at an angle to the wheel face, relative horizontal movement being permitted between the cutter and the wheel, an abutment having a vertical edge face normally fixed with respect to the wheel, means for effecting relative horizontal adjustment between the wheel and the abutment to cause the wheel face to always intersect the plane of the said tooth face along a line in predetermined fixed relation to the

face of the abutment, means supplemental to the cutter for determining the relative adjustment to the said line of intersection, and means including a former for guiding the relative horizontal movement between the 70 cutter and the wheel, the edge face of the former engaging the edge face of the abutment and being in predetermined fixed relation to the said tooth so that the tooth is ground to the contour of the former.

4. In a contour cutter grinding machine, the combination of a rotatable grinding wheel, a cutter support for holding a cutter with the front face of a tooth substantially horizontal and at an angle to the wheel face, 80 relative horizontal movement being permitted between the cutter and the wheel, an abutment having a vertical edge face normally fixed with respect to the wheel, means for effecting relative horizontal adjustment 85 between the wheel and the abutment to cause the wheel face to always intersect the plane of the said tooth face along a line in vertical alinement with the face of the abutment, means supplemental to the cutter for determining the relative adjustment to the said line of intersection, and means including a former for guiding the relative horizontal movement between the cutter and the wheel, the edge face of the former engaging the 90 edge face of the abutment and being in vertical alinement with the said tooth so that the said tooth is ground to the contour of the former.

5. In a contour cutter grinding machine, 100 the combination of a rotatable grinding wheel, a cutter support for holding a cutter with the front face of a tooth substantially horizontal and at an angle to the wheel face, relative horizontal movement being permitted between the cutter and the wheel, an abutment having a vertical edge face normally fixed with respect to the wheel, a dressing tool movable along a line in the plane of the said tooth face and in fixed relation to the face of the abutment, means for effecting relative horizontal adjustment 105 between the wheel and the tool to cause engagement whereby the grinding face is always maintained at the said line notwithstanding wear, and means including a 110 former for guiding the relative horizontal movement between the cutter and the wheel, the edge face of the former engaging the edge face of the abutment and being in fixed relation to the tooth so that the said tooth is ground to the contour of the former.

6. In a contour cutter grinding machine, the combination of a rotatable grinding wheel, a cutter support for holding a cutter 125 with the front face of a tooth substantially horizontal and at an angle to the wheel face, relative horizontal movement being permitted between the cutter and the wheel, an abutment having a vertical edge face 130

normally fixed with respect to the wheel, a dressing tool movable along a line in the plane of the said tooth face and in vertical alinement with the face of the abutment, 5 means for effecting relative horizontal adjustment between the wheel and the tool to cause engagement whereby the grinding face is always maintained at the said line notwithstanding wear, and means including 10 a former for guiding the relative horizontal movement between the cutter and the wheel, the edge face of the former engaging the edge face of the abutment and being in vertical alinement with the tooth so that 15 the said tooth is ground to the contour of the former.

7. In a contour cutter grinding machine, the combination of a rotatable grinding wheel, a cutter support for holding a cutter 20 with the front face of a tooth substantially horizontal and at an angle to the wheel face, relative horizontal movement being permitted between the cutter and the wheel, an abutment having a vertical edge face 25 normally fixed with respect to the wheel, means for adjusting the wheel horizontally to cause the wheel face to always intersect the plane of the said tooth face along a line in vertical alinement with the face of the 30 abutment, means supplemental to the cutter for determining the adjustment of the wheel to the said line, and means including a former for guiding the relative horizontal movement between the cutter and the wheel, 35 the edge face of the former engaging the edge face of the abutment and being in vertical alinement with the said tooth so that the tooth is ground to the contour of the former.

40 8. In a contour cutter grinding machine, the combination of a normally fixed rotatable grinding wheel, a horizontally movable cutter support for holding a cutter with the front face of a tooth substantially horizontal and at an angle to the wheel face, a normally fixed abutment having a vertical edge face, means for effecting relative horizontal adjustment between the wheel and the abutment to cause the wheel face to 45 always intersect the plane of the said tooth face along a line in vertical alinement with the face of the abutment, means supplemental to the cutter for determining the adjustment of the wheel to the said line, and 50 means including a movable former for guiding the horizontal movement of the cutter, the edge face of the former engaging the edge face of the abutment and being in vertical alinement with the said tooth so that 55 the tooth is ground to the contour of the former.

9. In a contour cutter grinding machine, the combination of a normally fixed rotatable grinding wheel, a horizontally movable cutter support for holding a cutter 60

with the front face of a tooth substantially horizontal and at an angle to the wheel face, a normally fixed abutment having a vertical edge face, a dressing tool movable along a line in the plane of the said tooth face and 70 in vertical alinement with the face of the abutment, means for effecting relative horizontal adjustment between the wheel and the tool to cause engagement whereby the grinding face is always maintained at the 75 said line notwithstanding wear, and means including a movable former for guiding the horizontal movement of the cutter, the edge face of the former engaging the edge face of the abutment and being in vertical alinement with the said tooth so that the tooth 80 is ground to the contour of the former.

10. In a cutter grinding machine, the combination of a rotatable grinding wheel, a cutter support for holding a cutter in engagement with the face of the wheel and for moving it horizontally relatively to the wheel to effect grinding along a predetermined normally fixed line, means for effecting relative vertical adjustment between 90 the cutter and the wheel, means for horizontally adjusting the wheel whereby its grinding face is always maintained at the said line notwithstanding the said relative vertical adjustment, and means supplemental to the cutter for determining the 95 relative horizontal adjustment to the said line.

11. In a cutter grinding machine, the combination of a rotatable grinding wheel, 100 a cutter support for holding a cutter in engagement with the face of the wheel, relative horizontal movement being permitted between the cutter and the wheel to effect grinding along a predetermined normally 105 fixed line, a dressing tool movable along the said line, means for effecting relative vertical adjustment between the cutter and tool and the wheel, and means for effecting relative horizontal adjustment between the 110 wheel and the tool whereby its grinding face is always maintained at the said line notwithstanding wear and notwithstanding the said relative vertical adjustment.

12. In a contour cutter grinding machine, 115 the combination of a rotatable grinding wheel, a cutter support for holding a cutter with the front face of a tooth substantially horizontal and at an angle to the wheel face, relative horizontal movement 120 being permitted between the cutter and the wheel, an abutment having a vertical edge face normally fixed with respect to the wheel, means for effecting relative vertical adjustment between the cutter and the 125 wheel, means for effecting relative horizontal adjustment between the wheel and the abutment to cause the wheel face to always intersect the plane of the said tooth face along a line in vertical alinement with the 130

- face of the abutment notwithstanding the said relative vertical adjustment, and means including a former for guiding the relative horizontal movement between the cutter and the wheel, the edge face of the former engaging the edge face of the abutment and being in vertical alinement with the said tooth so that the tooth is ground to the contour of the former.

13. In a contour cutter grinding machine, the combination of a rotatable grinding wheel, a cutter support for holding a cutter with the front face of a tooth substantially horizontal and at an angle to the wheel face, relative horizontal movement being permitted between the cutter and the wheel, an abutment having a vertical edge face normally fixed with respect to the wheel, a dressing tool movable along a line in the plane of the said tooth face and in vertical alinement with the face of the abutment, means for vertically adjusting the cutter and tool, means for effecting relative horizontal adjustment between the wheel and the tool to cause engagement whereby the grinding face is always maintained at the said line notwithstanding wear and notwithstanding the said vertical adjustment, and means including a former for guiding the relative horizontal movement between the cutter and the wheel, the edge face of the former engaging the edge face of the abutment and being in vertical alinement with the said tooth so that the tooth is ground to the contour of the former.

14. In a contour cutter grinding machine, the combination of a rotatable grinding wheel, a cutter support for holding a cutter with the front face of a tooth substantially horizontal and at an angle to the wheel face, relative horizontal movement being permitted between the cutter and the wheel, an abutment having a vertical edge face normally fixed with respect to the wheel, means for vertically adjusting the cutter, means for effecting relative horizontal adjustment between the wheel and the abutment to cause the wheel face to always intersect the plane of the said tooth face along a line in vertical alinement with the face of the abutment notwithstanding the said vertical adjustment, and means including a former for guiding the relative horizontal movement between the cutter and the wheel, the edge face of the former engaging the edge face of the abutment and being in vertical alinement with the said tooth so that the tooth is ground to the contour of the former.

15. In a contour cutter grinding machine, the combination of a rotatable grinding wheel, a cutter support for holding a cutter with the front face of a tooth substantially horizontal and at an angle to the wheel face, relative horizontal movement being permitted between the cutter and the wheel, an abutment having a vertical edge face normally fixed with respect to the wheel, means for effecting relative horizontal adjustment between the wheel and the abutment to cause the wheel face to always intersect the plane of the said tooth face along a line in vertical alinement with the face of the abutment notwithstanding the said vertical adjustment, and means including a movable former for guiding the horizontal movement of the cutter, the edge face of the former engaging the edge face of the abutment and being in vertical alinement with the said tooth so that the tooth is ground to the contour of the former.

16. In a contour cutter grinding machine, the combination of a normally fixed rotatable grinding wheel, a horizontally movable cutter support for holding a cutter with the front face of a tooth substantially horizontal and at an angle to the wheel face, a normally fixed abutment having a vertical edge face, means for effecting relative vertical adjustment between the wheel and the cutter, means for effecting relative horizontal adjustment between the wheel and the abutment to cause the wheel face to always intersect the plane of the said tooth face along a line in vertical alinement with the face of the abutment notwithstanding the said relative vertical adjustment, and means including a movable former for guiding the horizontal movement of the cutter, the edge face of the former engaging the edge face of the abutment and being in vertical alinement with the said tooth so that the tooth is ground to the contour of the former.

17. In a contour cutter grinding machine, the combination of a normally fixed rotatable grinding wheel, a horizontally movable cutter support for holding a cutter with the front face of a tooth substantially horizontal and at an angle to the wheel face, a normally fixed abutment having a vertical edge face, a dressing tool movable along a line in the plane of the said tooth face and in vertical alinement with the face of the abutment, means for effecting relative vertical adjustment between the cutter and tool and the wheel, means for effecting relative horizontal adjustment between the wheel and the tool to cause engagement whereby the grinding face is always maintained at the said line notwithstanding wear and notwithstanding the said relative vertical adjustment, and means including a movable former for guiding the horizontal movement of the cutter, the edge face of the former engaging the edge face

of the abutment and being in vertical alinement with the said tooth so that the tooth is ground to the contour of the former.

18. In a contour cutter grinding machine, 5 the combination of a rotatable grinding wheel, a cutter support for holding a cutter with the front face of a tooth substantially horizontal and at an angle to the wheel face, relative horizontal movement being 10 permitted between the cutter and the wheel, an abutment having a vertical edge face normally fixed with respect to the wheel, means for effecting relative horizontal adjustment between the wheel and the abut- 15 ment to cause the wheel face to always intersect the plane of the said tooth face along a line in predetermined fixed relation to the face of the abutment, means supplemental to the cutter for determining the relative 20 adjustment to the said line of intersection, means including a former for guiding the relative horizontal movement between the cutter and the wheel, the edge face of the former engaging the edge face of the abut- 25 ment, and means for effecting relative horizontal adjustment between the cutter and former to bring them into vertical alinement so that the said tooth is ground to the contour of the former.
- 30 19. In a contour cutter grinding machine, the combination of a rotatable grinding wheel, a cutter support for holding a cutter with the front face of a tooth substantially horizontal and at an angle to the wheel face, 35 relative horizontal movement being permitted between the cutter and the wheel, an abutment having a vertical edge face normally fixed with respect to the wheel, a dressing tool movable along a line in the 40 plane of the said tooth face, means for effecting relative horizontal adjustment between the wheel and the tool to cause engagement whereby the grinding face is always maintained at the said line notwithstanding wear, means including a former 45 for guiding the relative horizontal movement between the cutter and the wheel, the edge face of the former engaging the edge face of the abutment, and means for effect- 50 ing relative horizontal adjustment between the cutter and former to bring them into vertical alinement so that the said tooth is ground to the contour of the former.
20. In a contour cutter grinding machine, 55 the combination of a rotatable grinding wheel, a cutter support for holding a cutter with the front face of a tooth substantially horizontal and at an angle to the wheel face, relative horizontal movement being 60 permitted between the cutter and the wheel, an abutment having a vertical edge face normally fixed with respect to the wheel, means for effecting relative vertical adjustment 65 between the cutter and the wheel, means for effecting relative horizontal adjustment be-

tween the wheel and the abutment to cause the wheel face to always intersect the plane of the said tooth face along a line in predetermined fixed relation to the face of the abutment notwithstanding the said relative 70 vertical adjustment, means supplemental to the cutter for determining the relative adjustment to the said line of intersection, means including a former for guiding the relative horizontal movement between the 75 cutter and the wheel, the edge face of the former engaging the edge face of the abutment, and means for effecting relative horizontal adjustment between the cutter and former to bring them into vertical alinement so that the said tooth is ground to the 80 contour of the former.

21. In a contour cutter grinding machine, the combination of a grinding wheel, 85 a cutter support permitting relative movement between the cutter and the wheel and holding a cutter with the face of a tooth at an angle to the wheel face, a dressing tool positioned to engage the wheel face along a line in the plane of the said tooth face, an 90 abutment having its edge face in fixed perpendicular alinement with the aforesaid line, a guide having a definite relation to the abutment and serving as a means for setting the dressing tool, and means including a former engaging the abutment for guiding the relative movement between the cutter and the wheel.

22. In a contour cutter grinding machine, the combination of a normally fixed 100 grinding wheel, a movable cutter support, a movable dressing tool positioned to engage the wheel face along a predetermined line, an abutment having its edge face in fixed perpendicular alinement with the 105 aforesaid line, a guide movable with the dressing tool and positioned with its face in alinement with the face of the abutment, the guide serving as a means for setting the dressing tool, and means including a former 110 engaging the abutment for guiding the relative movement between the cutter and the wheel.

23. In a contour cutter grinding machine, the combination of a grinding wheel, 115 a bodily movable cross rail approximately parallel to the wheel axis, two saddles each carried by the cross rail and independently adjustable therealong, a dressing tool carried by one saddle and adapted to engage 120 the wheel face, and a cutter support carried by the other saddle and adapted to hold a cutter with the face of a tooth at an angle to the wheel face.

24. In a contour cutter grinding machine, 125 the combination of a grinding wheel, a bodily movable cross rail approximately parallel to the wheel axis, two saddles each carried by the cross rail and independently adjustable therealong, a dressing tool car- 130

ried by one saddle and adapted to engage the wheel face, a cutter support carried by the other saddle and adapted to hold a cutter with the face of a tooth at an angle to the wheel face, and means for adjusting the cutter support relatively to its saddle toward or from the wheel.

25. In a contour cutter grinding machine, the combination of a normally fixed grinding wheel, a bodily movable cross rail approximately parallel to the wheel axis, two saddles each carried by the cross rail and independently adjustable therealong, a dressing tool carried by one saddle and adapted to engage the wheel face, a cutter support carried by the other saddle and adapted to hold a cutter with the face of a tooth at an angle to the wheel face, and means for moving the cutter support relatively to its saddle and to the wheel to effect grinding of the cutter.

26. In a contour cutter grinding machine, the combination of a grinding wheel, a bodily movable cross rail approximately parallel to the wheel axis movable toward or from the grinding wheel, two saddles each carried by the cross rail and independently adjustable therealong, a dressing tool carried by one saddle and adapted to engage the wheel face, a cutter support carried by the other saddle and adapted to hold a cutter with the face of a tooth at an angle to the wheel face, and means for adjusting the wheel toward or from the dressing tool.

27. In a contour cutter grinding machine, the combination of a grinding wheel, a cutter support for holding a cutter in grinding relation with the wheel, manually operable means for effecting relative movement between the cutter and the wheel, a former in fixed relation with the cutter support for guiding the said relative movement, an abutment for the former, and means for maintaining a uniform pressure between the former and the abutment as relative movement occurs, the said uniform pressure being maintained irrespective of the pressure applied manually to effect relative movement.

28. In a contour cutter grinding machine, the combination of a normally fixed grinding wheel, a manually movable cutter support for holding a cutter in grinding relation with the wheel, a former movable with the cutter support for guiding the movement thereof, an abutment for the former, and means for maintaining a uniform pressure between the former and the abutment as the former is moved, the said uniform pressure being maintained irrespective of the pressure applied manually to effect movement of the cutter support and former.

29. In a contour cutter grinding machine, the combination of a normally fixed grind-

ing wheel, an angularly movable cutter support for holding a cutter in grinding relation with the wheel, a former movable with the cutter support for guiding the movement thereof, manually operable means for moving the cutter support and the former, an abutment for the former, and means for maintaining a uniform pressure between the former and the abutment as the former is moved, the said uniform pressure being maintained irrespective of the pressure applied manually to effect movement of the cutter support and former.

30. In a contour cutter grinding machine, the combination of a normally fixed grinding wheel, a movable cutter support for holding a cutter in grinding relation with the wheel, a former movable with the cutter support for guiding the movement thereof, an abutment for the former, means for maintaining a uniform pressure between the former and the abutment as the former is moved, and means for releasing the last said means to permit the former to be separated from the abutment.

31. In a contour cutter grinding machine, the combination of a normally fixed grinding wheel, a cutter support for holding a cutter in grinding relation with the wheel, a bodily movable pivot about which the cutter support is angularly movable, a former angularly movable with the cutter support about the said bodily movable pivot, and an abutment for the former enabling it to guide the combined bodily and pivotal movements of the cutter support.

32. In a contour cutter grinding machine, the combination of a normally fixed grinding wheel, a cutter support for holding a cutter in grinding relation with the wheel, a slide movable toward and from the wheel, a pivotal connection between the cutter support and the slide, a former movable with the cutter support relatively to the slide, and an abutment for the former enabling it to guide the combined bodily and pivotal movements of the cutter support.

33. In a contour cutter grinding machine, the combination of a grinding wheel, a cutter support for holding a cutter in grinding relation with the wheel, relative movement being permitted between the cutter and the wheel, a plurality of formers, and means for moving the formers relatively to the cutter support whereby any former may be used to guide the said relative movement between the cutter and the wheel.

34. In a contour cutter grinding machine, the combination of a grinding wheel, a cutter support for holding a cutter in grinding relation with the wheel, relative movement being permitted between the cutter and the wheel, an index wheel, and a plurality of formers connected with the index wheel whereby any one of them can be moved into

position to guide the said relative movement.

35. In a contour cutter grinding machine, the combination of a normally fixed grinding wheel, a movable cutter support for holding a cutter in grinding relation with the wheel, a plurality of formers bodily movable with the cutter support, and means

for moving the formers relatively to the cutter support whereby any former may be used to guide the said relative movement between the cutter and the wheel. 10

In testimony whereof, I hereto affix my signature.

FRIEDERICH MULLER.
